UNITED STATES PATENT OFFICE

DOLLNER S. FOLEY, OF MINNEAPOLIS, MINNESOTA

DESIGN FOR A TABLE LAMP

Application filed August 11, 1931. Serial No. 40,823. Term of patent 3½ years.

To all whom it may concern:

Be it known that I, DOLLNER S. FOLEY, a citizen of the United States, residing at Minneapolis, in the county of Hennepin and State of Minnesota, have invented a new, original, and ornamental Design for a Table Lamp, of which the following is a specification, reference being had to the accompanying drawing, forming part thereof.

The figure is a perspective view of the table lamp showing my new design.

I claim:

The ornamental design for a table lamp, as shown.

DOLLNER S. FOLEY.
